UNITED STATES PATENT OFFICE.

OVERTON WINSTON, OF MINNEAPOLIS, MINNESOTA.

HEADLIGHT.

1,346,519.

Specification of Letters Patent. Patented July 13, 1920.

Application filed March 27, 1916, Serial No. 86,851. Renewed December 12, 1919. Serial No. 344,463.

To all whom it may concern:

Be it known that I, Overton Winston, a citizen of the United States, residing at Minneapolis, in the county of Hennepin and State of Minnesota, have invented certain new and useful Improvements in Headlights; and I do hereby declare the following to be a full, clear, and exact description of the invention, such as will enable others skilled in the art to which it appertains to make and use the same.

My present invention relates to headlights for automobiles and other vehicles and is in the nature of an improvement on or modification of the bulb adjusting mechanism disclosed and claimed in my co-pending application S. N. 84773 filed of date, March 17, 1916 and entitled "Headlights," and also disclosed in certain other co-pending applications referred to in my said application just identified.

In the accompanying drawings which illustrate the invention, like characters indicate like parts throughout the several views.

Referring to the drawings:

Figure 1 is a vertical section taken centrally through a headlight embodying my invention;

Fig. 2 is a view partly in plan and partly in horizontal section on the line $x^2 x^2$ of Fig. 1, some parts being broken away;

Fig. 3 is a rear elevation of the electromagnetic bulb shifting mechanism showing the same as removed from the headlight;

Fig. 4 is a section taken on the line $x^4 x^4$ of Fig. 1, some parts being shown in full; and

Fig. 5 is a front end elevation of the lamp socket with the lamp removed.

The numeral 1 indicates the casing of an ordinary headlight, such as used on automobiles, and the numerals 2 and 3 indicate, respectively, the reflector and lens or glass plate of the headlight. The electric light bulb 4 illustrated, is of the well known Edison single base type, but of course, other types may be employed. As shown, however, this bulb has an outer contact sleeve 5 and an axial contact boss 6. The sleeve 5 of the light bulb is adapted to be telescoped into a holding collar 7 that is provided with an externally threaded eccentric portion 7^a that performs a novel and highly important function presently to be described.

The metallic sleeve 5 of the light bulb is

provided with three radially projecting lugs 8 adapted to be inserted into a corresponding number of internal longitudinal grooves 9 formed in the collar 7. At the inner extremities of the grooves 9, the collar 7 is provided with an annular shoulder formed with corrugations or serrations 10 with which the lugs 8 are adapted to be engaged.

The eccentric externally threaded portion 7^a of the holding collar 7 is screwed into the internally threaded portion of the sleeve 11 in which is secured an insulating plug 12 having axially mounted therein and projecting forward thereof, a spring-pressed contact plunger 13 that engages with the axial contact boss 6 of the light bulb, when the latter is in position. The so-called collar 7 and sleeve 11 constitute an axially adjustable lamp socket in which the sleeve 11 is the relatively fixed member and the collar 7 the relatively movable member, in so far as axial movements are concerned. The coiled spring 14 is preferably placed within the socket and compressed between the insulating plug 12 and the inner extremity of the eccentric portion 7^a of the collar or movable section 7. The spring 14 puts increased frictional engagement between the threaded engagement of members 7 and 11 and prevents accidental rotation of the said member 7 in respect to the said member 11.

In the drawings, the numeral 15 indicates one of the leads of a lamp circuit and which, as shown, is connected to the spring-pressed contact plunger 13. The other lead of the circuit is not shown but will be of any suitable metallic part through which the other lamp terminates and is grounded by contact 95 between the contact sleeve 5 and collar 7.

Provision is made for shifting the lamp socket so as to carry the filament of the light bulb toward and from the axis of the reflector 2. To this end, the lamp socket is 100 preferably pivoted for oscillatory movement in a vertical plane and, as shown, this pivot is provided by pivot screws 16 adjustably mounted in a hollow supporting head 17 and provided with conical points that engage small conical seats in the sides of the intermediate portion of the sleeve 11. The head 17 has a threaded shank screwed into the hub of an annular anchoring plate 18 that is secured to the back of the reflector 2 and surrounds an axial passage 2^a in the latter. The front end of the holding collar 7 pro-

jects through the passage 2^a and works with freedom for vertical and axial movements thereon.

For oscillating the lamp socket vertically, I provide upper and lower electro-magnets 19, both of which are rigidly secured to and carried by a hollow bearing head 17. As shown, the said head 17 is provided with laterally projecting flanged plates 17^a that are bolted to upper and lower cross plates 20 to which, in turn, the respective upper and lower electro-magnets 19 are directly secured. At their inner extremities, the electro-magnets are provided with pole pieces 19^a, and at their outer extremities with pole pieces 19^b. The pole pieces 19^a act upon and limit the oscillatory movements of the sleeve 11 of the lamp socket, and they are preferably formed with concave cylindrical surfaces of the same curve as the said sleeve 11, so that extended engagement therewith is afforded.

A small light spring 21, shown as a leaf spring, is anchored to the bearing head 17 and presses on the upper portion of the socket sleeve 11 at a point nearly above its pivot 16. This spring takes up all of the play which there may be between the conical ends of the pivot screws 16 and their seats in the sleeve 11, and hence, prevents rattling.

Small upper and lower lock levers 22 are intermediately pivoted to the upper and lower plates 20 and are provided at their inner ends with lock heads 23. The outer ends of said levers 22 are yieldingly pressed outward by light springs 24 shown as anchored to the respective plates 20. The outer ends of the said levers 22 serve as armatures that are adapted to be retracted by the outer pole piece 19^b of the respective electro-magnets. The circuit connections for the electro-magnets are not shown, but they are preferably independent of the lamp circuit and so arranged that either of the electro-magnets may be energized at will.

For illustration, let it be assumed that the externally threaded eccentric portion 7^a of the holding collar 7 has its axis offset one-thirty-second of an inch from the axis of the lamp holding portion of said collar. In this case, the best results are obtained by so mounting the sleeve 11 of the lamp socket that its axis, when horizontal, will be parallel with, but offset one-thirty-second of an inch from the axis of the reflector. With this arrangement, as is evident, when the lamp filament is at the axis of the lamp, such filament may, by rotation of the lamp and holding sleeve or movable section of the socket, be turned to a position in the axis of the reflector. If the filament of the lamp should be warped so that it is at one side of the axis of the lamp, the lamp should be rotated within the hold-

ing sleeve until the filament is carried to the circle described by the axis of the lamp when the holding sleeve 7 is rotated on its eccentric 7^a, and then by rotation of the said sleeve on its eccentric, the warped filament may be moved into the axis of the reflector. Thus it will be seen that by these compound adjustments, the filament of the lamp, whether at the axis of the lamp or at one side thereof, may be properly set at the axis of the reflector, it of course, being assumed in this statement that the lamp socket is then in a horizontal position.

Axial adjustments of the lamp to bring the filament thereof to the focal center of the reflector are produced by rotation of the holding socket 7 and 7^a, under which rotation, of course, the threaded engagement produces axial movements of the said holding sleeve and lamp. Of course, these rotary movements of the holding collar shift the lamp filament transversely of the axis of the reflector, but if such rotary adjustments of the collar always be complete rotations, then each rotation will always bring the lamp filament back to its properly set position. Furthermore, if the threads on the eccentric 7^a and in the sleeve 11 be very fine, then sufficiently accurate axial adjustment for focus may always be accomplished by imparting complete rotation to the holding collar.

By the means described, all of the required adjustments may be given to the lamp bulb by manipulation from within the reflector, and in fact, by engagement with the lamp bulb itself. The contact plunger 13, as stated, is spring-pressed into engagement with the contact boss 6, and it therefore follows that the lugs 8 will be yieldingly held in engagement with the corrugations 10 so that if the lamp be turned without pressing the same inward or backward, then the collar 7 and its eccentric 7^a will be rotated therewith. If, however, the lamp be first pressed rearward so as to disengage its lugs 8 from the corrugations 10, then the lamp may be rotated within the said holding collar without rotating the latter. The spring 14 adds an additional frictional engagement between the threads of the eccentric 7^a and sleeve 11, so that rotation of the collar 7 when the lamp is pressed rearward and rotated, is further prevented.

In Fig. 1, the full lines show the lamp socket lowered and the lamp raised so that its filament is then above the axis of the reflector, as required for short distance projection of the light beams. In this position of the parts, the head 23 of the upper lock lever 22 is between the rear end of the socket sleeve 11 and the pole piece 19^a of the upper electro-magnet 19. When the lamp socket is to be raised and the lamp moved downward so that its filament will

be at the axis of the reflector, as indicated by dotted lines in Fig. 1, the upper electro-magnet 19 must be first energized. The first effect of this is to cause the pole piece 19^b of the upper electro-magnet, acting on the upper lock lever 22, to move the head of the latter out of the path of movement of the rear end of the socket sleeve 11, and the second effect is to cause the electro-magnet 10 to raise the lamp socket and lower the light bulb as stated. Under upward movement of the lamp socket, the head 23 of the lower lock lever 22 is cammed out of its way, but when the said socket reaches its 15 uppermost position, the spring 24 of the said lower lock lever will cause the head 23 of said lever to engage between the rear end of the socket sleeve 11 and the pole piece 19^a of the lower electro-magnet, thus 20 locking the lamp socket in its raised position, with the filament of the lamp at the axis of the reflector. Of course, the reverse or downward movement of the socket is produced by energizing the lower magnets, 25 and under the downward movement thereof, the upper lock lever will be automatically engaged therewith and securely hold the same in its lowered position with the filament of the lamp above the axis of the 30 reflector.

It will be noted further that the lamp socket, the magnet and lock levers are all supported by the removable supporting head 17 so that the said elements may be 35 all removable together as a self-contained operatively connected structure. Removal of these parts of course, requires that the light bulb be first removed from the socket, because the light bulb will not pass through 40 the opening 2^a in the back of the reflector. Furthermore, when the said devices are applied in working position they are supported entirely from the reflector.

The above described three-point interlocking connection between the lamp and socket is also important. Usually, one or sometimes two lock lugs and co-operating grooves are employed, but neither of such arrangements provides the best means for 50 connecting the lamp socket. It is a well known fact that three points determine the position of a plane, and on the same principle, the engagement of the three lugs 8, with three corrugations 10 will determine 55 the position of the axis of the lamp in respect to the axis of the socket, it, of course, being assumed that there is some play between the contact sleeve 5 of the lamp and the surrounding seat therein in the holding 60 collar 7.

This feature of the three-point contact is not herein claimed but is disclosed and claimed in my companion application S. N. 84,773, above noted.

65 In Fig. 1, the heavy dots marked y and y'

indicate, respectively, the hot spot of the lamp filament when at the axis of the reflector and when raised above the axis of the reflector by oscillatory movements of the lamp socket, and it will be noted that 70 these extreme positions are vertical, one directly over the other. Otherwise and more broadly stated, the said two points y and y' are in a common plane that is at a right angle to the axis of the reflector. 75 With a parabolic reflector and a light bulb of the usual construction, the best results are obtained by arranging the lamp socket for the movements above described. Such movement sets the lamp so that the projected beam will be free from dark rings, both in the adjustment for long beam projection and for the adjustment for the shorter range projection.

What I claim is:

85 1. A lamp holding socket comprising a relatively fixed sleeve and a lamp holding collar having threaded engagement therewith, in combination with a lamp rotatably adjustable in said collar and adapted to be set therein in different rotary adjustments in respect thereto.

2. A lamp holding socket comprising a relatively fixed sleeve and lamp holding collar having threaded engagement therewith, 95 in combination with a lamp rotatably adjustable in said collar and adapted to be set therein in different rotary adjustments in respect thereto, and a spring interposed between the said sleeve and collar for putting 100 increased friction on the threaded engagement between the two.

3. In a headlight, the combination with a reflector and a socket support, of a lamp socket adjustably mounted on said support 105 and comprising relatively fixed and movable sections, the one section being provided with a threaded eccentric portion having a threaded engagement with the other section, and an electric light bulb rotatively mounted 110 in the adjustable section of said socket.

4. In a headlight, the combination with a reflector and a socket support, of a lamp socket adjustably mounted on said support 115 and comprising relatively fixed and movable sections, the one section being provided with a threaded eccentric portion having a threaded engagement with the other section, an electric light bulb rotatively mounted in the adjustable section of said socket, and 120 having releasable interlocking engagement therewith whereby the said bulb may be rotated therewith or independently thereof.

5. In a headlight, the combination with a reflector and a socket support, of a lamp 125 socket adjustably mounted on said support and comprising relatively fixed and movable sections, the one section being provided with a threaded eccentric portion having a threaded engagement with the other section,

130

an electric light bulb rotatively mounted in the adjustable section of said socket, having releasable interlocking engagement therewith whereby the said bulb may be rotated therewith or independently thereof, and a spring-pressed contact tending to maintain the interlocking engagement between said bulb and adjustable socket section.

6. In a headlight, the combination with a reflector and a socket support, of a lamp socket adjustably mounted on said support and comprising relatively fixed and movable sections, the one section being provided with a threaded eccentric portion having a threaded engagement with the other section, an electric light bulb rotatively mounted in the adjustable section of said socket, and having releasable interlocking engagement therewith whereby the said bulb may be rotated therewith or independently thereof, and a spring increasing the friction between the engaging threads of said socket sections.

7. A lamp socket comprising an internally threaded sleeve, and a holding collar, the latter having an externally threaded eccentric adjustably engaging the threaded portion of said socket sleeve, and a light bulb rotatively mounted in said holding collar.

8. A lamp socket comprising an internally threaded sleeve, and a holding collar, the latter having an externally threaded eccentric adjustably engaging the threaded portion of said socket sleeve, a light bulb rotatively mounted in said holding collar, and having releasable interlocking engagement

therewith, whereby the said lamp may be rotated with or independently of said holding collar.

9. A lamp socket comprising an internally threaded sleeve, and a holding collar, the latter having an externally threaded eccentric adjustably engaging the threaded portion of said socket sleeve, a light bulb rotatively mounted in said holding collar, and a spring-pressed contact normally engaging an axial contact on the shank of said light bulb and tending to maintain the interlocking engagement between the same and said holding collar.

10. In a headlight, the combination with a reflector having an axial passage, of an anchoring plate secured to the back of said reflector and alined to axial passage thereof, a supporting head having threaded engagement with said anchoring plate, a socket adjustably mounted on said supporting head in position to support a lamp within said reflector, and electro-magnetic devices for adjusting said socket, also mounted on said supporting head, the said head, lamp socket and socket actuating means being removable from said reflector, as a self-contained operatively assembled structure.

In testimony whereof I affix my signature in presence of two witnesses.

OVERTON WINSTON.
